UNITED STATES PATENT OFFICE.

JOSEPH BORGHES AND JAMES F. STAHLER, OF SEATTLE, WASHINGTON.

AUTOMATIC AUTO-JACK.

1,369,610.

Specification of Letters Patent. Patented Feb. 22, 1921.

Application filed March 23, 1920. Serial No. 368,200.

To all whom it may concern:

Be it known that we, JOSEPH BORGHES, and JAMES F. STAHLER, citizens of the United States of America, and residents of 5 the city of Seattle, in the county of King and State of Washington, have invented certain new and useful Improvements in Automatic Auto-Jacks, of which the following is a specification.

10 Our invention relates to an improvement in automatic auto jacks.

The object of our invention is to provide means which may be installed as a permanent part of a garage or storage shed 15 which will support an automobile by its axles, leaving all of the wheels free from supporting engagement with the garage floor.

Another object of our invention is to provide 20 such an auto jack which will operate automatically to raise the automobile through the use of the power of the machine itself.

Another object of our invention is to provide 25 an auto jack of this character which may be released to lower the car, from the driver's seat.

Another object of our invention is to provide 30 in an auto jack means whereby the jack arms supporting the front and rear axles are independently operated.

Another object of our invention is the provision of means in such an auto jack for raising the rear wheels of the car above the 35 rear jack arm, and the combination therewith of means operable by the motion of the car for collapsing the wheel support to permit the rear end of the car to be supported entirely upon its rear axle.

40 Our invention comprises those novel parts and combinations thereof which are shown in the accompanying drawings, described in the specification and particularly defined by the claims terminating the same.

45 In the accompanying drawings we have shown our invention in a form which is now preferred by us.

Figure 1 is a plan view of our invention, parts being shown in position to be engaged 50 by a car to support the same.

Fig. 2 is a side elevation of our device.

Fig. 3 is a detail view showing in side elevation the rear supporting means and the mechanism connected therewith.

55 Fig. 4 is a longitudinal section through

our device, parts being shown in the position they would occupy just prior to their being locked in vehicle-supporting position.

Fig. 5 is an elevation of the rear end support, parts being shown in the vehicle-supporting position.

Fig. 6 is a longitudinal section through the front supporting mechanism and the locking and releasing mechanism therefor, parts being shown in the vehicle-supporting 60 position.

Fig. 7 is a plan view of one of the trip levers which we employ.

Essentially our device consists of front jack arms 1 and rear jack arms 2 which are 70 spaced sufficiently to engage beneath the front and rear axles, respectively, of an automobile to thereby support the car, and which are pivoted upon transverse axes 10 and 20, respectively, so that they may swing 75 longitudinally of the direction of motion of the car. We prefer that these jack arms 1 and 2 be formed in pairs to engage the opposite sides of the center line of the car. The rear jack arm 2 normally is low enough 80 to permit the car to pass over it without engaging the arm. The front arm 1, however, is normally positioned to be engaged by the front axle 31 of an automobile 3 and to support the axle upon its upper end when the 85 arm 1 is swung into vehicle-supporting position.

The front jack arms 1 are operable independently of the rear jack arms 2, and we shall first describe their construction and operation. The car 3, in being driven upon the jack, engages the arms 1 or the lugs 11 upon the upper ends thereof by its front axle, 31. If desired an incline 41 may be placed in position at each side of the frame 90 4, upon which the front wheels may rise to any desired height. As the front axle 31 engages the jack arms 1, the car progressing forward under its own power through the traction of the rear wheels, the front axle is 95 raised upon the jack arms 1. We provide a bumper 40 which may have a resilient block 42 in position to be engaged by the jack arms 1 to limit their forward swing. Preferably the forward swing of the arms 1 is arrested 100 in such position that the center of support of the axle 31 upon the jack arms 1 is slightly to the rear of the pivot 10 of the jack arms.

To secure the jack arms in vehicle-sup- 110

porting position we may provide a locking hook 12 which is pivoted upon the jack arms or upon a rod 14 extending therebetween, and which is engageable with a rod 43 extending between the pair of bumpers 40. When the jack arms 1 are raised into vehicle-supporting position the hook 12 engages over the bar 43 to secure the arms in raised position. The hook 12 may also be provided with a second hook 13 which is adapted to engage the bar 43 to limit the rearward movement of the jack arms 1 and to hold them in position to be engaged by the axle 31.

As a means for releasing the locking hook 12 we provide a lever 5 which is rotatable upon the bar 43 and which is provided with a releasing dog 51 engageable beneath the hook 12. A bell-crank lever 52 having one end slotted, as shown at 53, and engaging with the lever 5, may be connected by means of a rod 54 to a release lever 55 which is positioned to be operable from the driver's seat. By pulling rearwardly upon the releasing lever 55 the releasing dog 51, through the connection described, will lift the hook 12 from its engagement with the bar 43 and will permit the jack arms 1 to swing rearwardly under the influence of the weight of the car.

While the rear jack arms 2 are normally positioned below the car where they will not be engaged thereby, means are provided for raising said jack arms into vehicle-supporting position. Preferably these means are operable through the forward motion of the car itself. The means which we have shown herein consists of the rod 21 which extends forward from a split rod 22 secured to each of the jack arms 2, and which is provided at its forward end with a hook 23 adapted to engage the front axle 31 of the car 3. A yoke 44 may be employed to support the forward end of the bar 21 if desired. It is apparent that as the vehicle moves forward when the hook 23 has engaged the front axle 31, as best shown in Fig. 4, the rear jack arms 2 will be raised into vehicle-supporting position beneath the rear axle 32.

It is not desired that the momentum of the car shall be sufficient to carry the car up upon the arms 2 as they swing upward, as this would severely strain the jack. The rear end of the car, therefore, must be raised above the arms 2 and then lowered thereupon. As a means for accomplishing this result we have provided the auxiliary supports 6 for the rear wheels of the vehicle. These means comprise the boards 6 which are pivoted at one end, as at 60, and which are provided with supporting means for their outer ends. As shown these supporting means comprise the levers 61 which are pivoted in the outer end of the boards 6

at 62. These levers 61 may be formed as U-shaped yokes having secured thereto at their ends the rollers 63 which are adapted to roll upon the floor. The central portion 64 of the levers 61 forms a tripping member, the operation of which will be later described.

A setting mechanism for the supporting levers 61 is provided, this being operable by the forward motion of the car. This consists of a lever formed of two parts. The upper part 70 is pivoted at 71 to the lower section 7 of the lever by a suitable spring hinge, so that it will bend if engaged from one side but will form an integral part of the whole setting lever if engaged from the other side. The lower section may be pivoted to the floor by a similar spring hinge 72 which is adapted to maintain the lever 7 in operative position and to return it to operative position after it has been tripped. This lever 7 is connected through a suitable draw-bar 73 to a lever 74 which is secured upon a shaft 75. At its ends this shaft 75 is bent downward and is formed with a toe 76 which engages beneath the supporting lever 61 to raise the same into supporting position.

The auxiliary support 6 is normally in inoperative or collapsed position. After the front wheels of the car have passed over the support 6 the front axle or other suitable member upon the automobile engages the setting lever 7, which is drawn forward. This raises the lifting toe 76 and the lever 61 is thereby raised into approximately vertical position to hold the auxiliary support 6 in inclined position as shown in Fig. 4. A spring 67 may be employed to engage and prevent accidental collapse of the lever 61. After the front axle 31 has passed on beyond the tripping lever 7 this resumes its normal position and the lifting toe 76 is dropped to its normal position. The supporting lever 61, however, remains raised. The rear wheels 33 of the automobile ride upward upon the inclined auxiliary supports 6 until the rear axle 32 is immediately above the rear jack arms 2, which in the meantime have been raised into vehicle-supporting position, as has been described. Upon further forward motion of the vehicle the periphery of the rear wheels 33 strikes the release member 64, pushing it forward and causing the lever 61 which supports the auxiliary supports 6 to fold and to collapse. The auxiliary supports 6 are thereby collapsed into their normal flat position and the rear axle 32 of the vehicle is lowered and supported upon the rear jack arms 2 with the wheels 33 free from supporting engagement.

To release the device the releasing lever 55 is pulled as has been described, and the weight of the car, being slightly off center of the pivots of the jack arms, will cause

the jack arms 1 and 2 to swing rearwardly. The car is thus deposited once more upon its wheels. In backing out the section 70 of the tripping lever 7 will fold downward 5 when engaged by the front axle 31 and will not be operable to reset the auxiliary support 6 until engaged from the opposite side.

By the use of a device of this kind an automobile may be lifted from its wheels 10 by the use of its own motive power and may be thus supported by its axles for as long a period of time as is desired. This is of great advantage in saving the tires and preventing collapse of the side walls thereof.

15 What we claim as our invention is:

1. An automatic auto jack comprising pivoted front and rear jack arms engageable respectively with the vehicle front and rear axles to support the car, said front jack arms 20 being normally inclined and in position to be engaged by the vehicle front axle, and a rod having a hook at one end engageable by the vehicle front axle and operable by its forward motion for swinging said rear jack 25 arm upward beneath the vehicle to thereby support its rear end, said front jack arm being also swung upward with the forward motion of the vehicle into position to support its front end.

30 2. An automatic auto jack comprising pivoted front and rear jack arms, said front arm being adapted to engage the vehicle front axle to be raised into vehicle-supporting position by its forward motion and said 35 rear jack arm being inclined rearwardly in inoperative or in vehicle-supporting positions, a rod having a hook at one end engageable directly upon the vehicle and connected by its other end directly to said rear 40 jack arm, and operable by the forward motion of the vehicle to swing said rear jack arm upward beneath the rear axle into vehicle-supporting position, and means for locking said parts in vehicle-supporting position.

45 3. An automatic auto jack comprising pivoted front and rear jack arms, said front jack arm being positioned to be engaged by the vehicle front axle during the forward motion thereof, thereby to raise and support the same, both front and rear jack arms being inclined rearwardly in inoperative or in vehicle-supporting positions, a rod having a hook at the forward end engageable by the 50 vehicle front axle and connected directly to said rear jack arms, and operable by the forward motion of the vehicle to swing said rear jack arms upward beneath the rear axle to support it, and releasable means for securing said members in vehicle supporting 55 position.

60 4. An automatic auto jack comprising pivoted front and rear jack arms, said front jack arm being positioned to be engaged by the vehicle front axle during the forward 65

motion thereof, thereby to raise and support the same, means engageable by the vehicle and operable by its forward motion to swing said rear jack arms upward beneath the rear axle to support it, an auxiliary support for the 70 rear wheels of the vehicle in operative position while said rear jack arm is being swung into vehicle-supporting position, and means operable by further forward motion of the vehicle thereafter for collapsing said auxiliary support.

75 5. An automatic auto jack comprising pivoted front and rear jack arms, said front jack arm being positioned to be engaged by the vehicle front axle during the forward motion thereof, thereby to raise and support the same, means engageable by the vehicle and operable by its forward motion to swing said rear jack arms upward beneath the rear axle to support it, an auxiliary support for 80 the rear wheels of the vehicle in operative position while said rear jack arm is being swung into vehicle-supporting position, a lever pivoted upon the outer end of said incline and adapted to support the same in inclined position, and a trip lever forming a part of said supporting lever, and adapted to be engaged by the vehicle wheel to release 85 said supporting lever.

90 6. An automatic auto jack comprising pivoted front and rear jack arms, said front jack arm being positioned to be engaged by the vehicle front axle during the forward motion thereof, thereby to raise and support the same, means engageable by the vehicle 95 and operable by its forward motion to swing said rear jack arms upward beneath the rear axle to support it, an auxiliary support for the rear wheels of the vehicle normally in inoperative position, means actuated by the forward movement of the vehicle for raising said auxiliary support to be in supporting 100 position while said rear jack arm is being swung into vehicle-supporting position, and means operable by further forward motion 105 of the vehicle thereafter for collapsing said auxiliary support.

110 7. An automatic auto jack comprising pivoted front and rear jack arms, said front jack arm being positioned to be engaged by the vehicle front axle during the forward motion thereof, thereby to raise and support the same, means engageable by the vehicle and operable by its forward motion to swing said rear jack arms upward beneath the rear 115 axle to support it, an auxiliary support for the rear wheels of the vehicle normally in inoperative position, means engageable by the front axle of the vehicle in moving forward positioned ahead of said auxiliary support for raising the same into inclined position, a member supporting said auxiliary support in inclined position, and means operable by the forward motion of the vehicle for collapsing said inclined aux- 120 125 130

iliary support when said rear jack arms are in vehicle-supporting position beneath the rear axle.

8. An automatic auto jack comprising 5 pivoted front and rear jack arms, said front jack arm being positioned to be engaged by the vehicle front axle during the forward motion thereof, thereby to raise and support the same, a rod extending forward be- 10 neath the car and provided at its forward end with an axle-engaging hook, and connected at its rear end to the rear jack arm to raise said arm into vehicle-supporting position beneath the rear axle after engagement 15 of said hook with the front axle, a bumper limiting the forward movement of said front jack arm, a locking bar carried thereby, and a hook carried by said front jack arm and engageable with said locking bar to 20 prevent rearward motion of the jack arms.

9. An automatic auto jack comprising pivoted front and rear jack arms, said front jack arm being positioned to be engaged by the vehicle front axle during the forward 25 motion thereof, thereby to raise and support the same, a rod extending forward beneath the car and provided at its forward end with an axle-engaging hook, and connected at its rear end to the rear jack arm to raise said 30 arm into vehicle-supporting position beneath the rear axle after engagement of said hook with the front axle, a bumper limiting the forward movement of said front jack arm, a locking bar carried thereby, and a 35 hook carried by said front jack arm and engageable with said locking bar to prevent rearward motion of the jack arms, an auxiliary support for the rear wheels of the vehicle in operative position while said jack 40 arm is being swung into vehicle-supporting position, and means operable by further forward motion of the vehicle thereafter for collapsing said auxiliary support.

10. An automatic auto jack comprising 45 spaced front and rear jack arms, said front jack arm being normally positioned to be engaged by the vehicle front axle to be

swung upward and forward into vehicle-supporting position, an auxiliary support for the rear wheels, means engageable by the vehicle and operable by forward movement thereof for supporting said auxiliary support in operative position, means engageable by the vehicle and operable by its forward motion for raising said rear jack arm 55 into vehicle-supporting position beneath the vehicle rear axle, and means operable by further forward motion of the vehicle for collapsing said auxiliary support.

11. In an automatic auto jack, a rear jack 60 arm, means for raising said jack arm beneath the rear end of the car into car-supporting position, an auxiliary support for the rear wheels, means for raising said auxiliary support into inclined position, and 65 means operable by forward motion of the car for lowering said auxiliary support to lower the rear end of the car upon said jack arm.

12. In an automatic auto jack, a rear jack 70 arm, means for raising said jack arm beneath the car into car-supporting position, auxiliary supports for the rear wheels, means for raising said auxiliary supports 75 into inclined position during forward motion of the car, and means operable by the car upon further forward motion for lowering said auxiliary supports to lower the rear end of the car.

13. In an automatic auto jack, a rear jack 80 arm, means operable by the car during its forward motion to raise said jack arm beneath the car into car-supporting position, auxiliary supports for the rear wheels, means for raising said auxiliary supports 85 into inclined position during forward motion of the car, and means operable by the car at the limit of its forward motion for lowering said auxiliary supports to lower the rear end of the car upon said jack arm. 90

Signed at Seattle, Washington, this 17th day of March, 1920.

JOSEPH BORGES.
JAMES F. STAHLER.
